UNITED STATES PATENT OFFICE

JAMES B. McWILLIAMS, OF PITTSBURGH, PENNSYLVANIA, ASSIGNOR TO RAILWAY MAINTENANCE CORPORATION, OF PITTSBURGH, PENNSYLVANIA, A CORPORATION OF PENNSYLVANIA

RAILWAY BALLAST HANDLING MACHINE

Application filed June 30, 1927. Serial No. 202,693.

This invention relates to railway ballast handling machines. It is effective for digging ballast from the space between adjacent railway tracks and under the ends of the ties 5 of such tracks, screening the ballast, returning the cleaned material to the road bed, and conveying the screenings to a convenient point.

A railway road bed comprises a sub-base 10 which is generally rolled hard and is horizontal, when considered crosswise of the right of way. A layer of stone ballast lies on this sub-base and carries the rail ties. The ballast is of generally uniform depth on 15 straight pieces of track, but varies in depth at curves because of the inclination of the tracks.

Dust and dirt which settle on the road bed are washed into the ballast so that in time it 20 loses its porous and elastic character and does not drain properly. When this condition arises, the rails begin to "pump" and the quality of the road bed rapidly deteriorates. It is therefore necessary to periodically 25 clean the ballast so as to restore its porous and elastic character. Experience shows that cleaning between adjacent tracks is sufficient to keep the road bed in good condition, provided the cleaning extends sufficiently close to the ties of the adjacent tracks. Unless the cleaning is extended sufficiently 30 close to the ties there remains a substantially impervious wall which prevents drainage of those portions of the ballast which actually support the tracks.

Ballast has heretofore been cleaned almost entirely by hand labor. Some machines for doing this work have been proposed, but they have generally been open to numerous 40 objections. Some of them have been mounted on the railroad rails and have therefore interfered with railway traffic. Others have been arranged for support by the ties so that they would not interfere with railway traffic, 45 but these machines have lacked the flexibility required, and have failed to attain their object on curves. As above pointed out, the sub-base of a railroad track is substantially horizontal, but at a curve the tracks are at 50 different elevations and the machines hereto-

fore proposed have not been designed to meet this condition. They have lacked the necessary clearance when supported on ties of different elevation and have been unsuited to digging down to a horizontal sub-base. 55

I provide a machine comprising a frame which fits into a trench initially dug between the ties of adjacent rails, and is supported on rails carried by the ties. The machine is arranged to automatically advance and dig 60 its way into the ballast. I preferably employ digging arms which, during at least a portion of their movement, extend sidewise of the machine proper so as to dig sufficiently close to the ends of the ties to break down the impervious wall which other machines have not been able to reach. The digging arms are effective for digging out the entire space between the tracks. I preferably employ double pointed digging arms, as these are more 65 effective for digging. This type of arm will dig to the side wall of the trench, as well as the bottom thereof, and the points preserve sufficient clearance for the body of the arm and eliminate undue loads on the digging 70 head and driving mechanism. The arms are preferably so arranged that during a portion of their stroke they both lie within the side- 75 wise limits of the machine, so that it may be readily inserted in the trench. 80

My improved machine is effective for elevating the dug ballast and screening the same so as to remove the dirt. The cleaned ballast is returned to the trench at the rear of the machine and the screenings are elevated so as 85 to permit of ready disposal.

The machine is so constructed that it does not interfere with normal railway traffic in any way. A major portion of the machine lies in the trench, thus permitting of using 90 rugged construction and within the clearance limits. In order to take care of conditions at curves, I provide supporting means on opposite sides of the machine, which supporting means are relatively vertically adjustable. 95 Despite differences in the elevation of ties on adjacent railroad tracks, the machine may be kept horizontal and clear of rail traffic at all times.

I provide an improved drive mechanism 100

whereby great flexibility of operation and long life of the machine are insured.

In the accompanying drawings, which illustrate the present preferred embodiment of the invention and certain modifications thereof,

Figure 1 is a perspective view of the machine, looking on it from the top,

Figure 2 is a side elevation,

Figure 3 is a front elevation showing the machine in operation,

Figure 4 is a top plan view with certain of the parts removed so as to show the driving connections,

Figure 5 is a vertical section taken on the line V—V of Figure 4,

Figure 6 is a top plan view to enlarged scale of the digging head.

Figure 7 is a view to still larger scale taken on the line VII—VII of Figure 6.

Figure 8 is a top plan view partly broken away, showing a supporting rail,

Figure 9 is a side elevation of Figure 8,

Figure 10 is a cross sectional view through a supporting rail taken on the line X—X of Figure 8.

Figure 11 is a side elevation to enlarged scale of one of the supporting brackets for the machine,

Figure 12 is a top plan view of a screening conveyor which may be employed with the machine,

Figure 13 is a side elevation of the conveyor shown in Figure 12,

Figure 14 is a view corresponding to Figure 6, but showing a modified form of digger head, and

Figure 15 is a view to enlarged scale taken on the line XV—XV of Figure 14.

Figure 1 shows the general construction of the machine. It comprises a frame 2 having brackets 3 pivotally mounted thereon at 4. The brackets have sidewise extending arms 5 carrying supporting wheels 6 at the front of the machine, and combined supporting and traction wheels 7 at the rear. The front of the machine is inclined and carries a plate 8. A digging arm 9 is arranged on each side of this plate. Each arm 9 is effective for digging ballast and sweeping it toward the foot portion 10 of a conveyor 11. The conveyor elevates the ballast and transports it to the rear of the machine where it is dumped on a shaking screen 12.

The screened ballast falls off the discharge lip 13 at the rear of the machine, while the screenings fall into a hopper and are carried off by a conveyor 14.

Drive mechanism

See particularly Figures 1, 2 and 4.

The power is supplied by an internal combustion engine 15 mounted on cross brackets 16. The engine is arranged longitudinally of the machine and a special cranking shaft

17 is therefore provided. This shaft extends upwardly and sidewise. It is connected through suitable gearing (not shown) to the engine crank shaft. A radiator 19 and cooling fan 20 are arranged alongside the engine. 70

As will be seen from Figure 2, a large part of the engine is arranged below the tie level T. L., and due to the digging and screening operations, the engine necessarily works under very adverse conditions. An air cleaner 21 is provided so as to keep dust and grit out of the engine cylinders. 75

The engine 15 is provided with a clutch 22 having an operating handle 23. Engine power is transmitted through the clutch to a bevel pinion 24. The bevel pinion meshes with a bevel gear 25 mounted on a cross shaft 26. A jaw clutch 27 having an actuating lever 28 is mounted on the shaft 26 and controls a sprocket 29. By actuating the lever 28, the sprocket 29 may be driven or left free, as desired. A sprocket chain 30 extends from the sprocket 29 to a sprocket 31. It is guided by an idler 32. The sprocket 31 is carried by a shaft 33 through which the digger arms 9 are driven. The shaft 33 carries sprockets 34 connected through chains 35 to sprockets 36. The sprockets 36 are each keyed to worm shafts 37. Each shaft 37 carries a worm 38 meshing with a worm wheel 39. Each worm wheel is mounted on a shaft 40 formed integral with a disk 41 which lies substantially flush with the plate 8. Each disk 41 carries a crank pin 42 engaging an arm 9. 90

The shaft 26 carries a sprocket 43 connected through a chain 44 to a sprocket 45 on a cross shaft 46. The cross shaft 46 carries a sprocket 47 connected through a chain 48 to a sprocket 49 on a shaft 50. The shaft 50 forms the head shaft of the conveyor 11. 95

The shaft 46 makes a chain and sprocket connection 51 with a shaft 52 which drives the shaker screen. It also makes a chain and sprocket connection 53 with a shaft 54, which is the foot shaft of the screenings elevator 14. 110

The shaft 46 also carries a pinion 55 meshing with a gear 56 on the driving shaft 57 of a gear box 58. The gear box is provided with operating levers 59. The traction wheels 7 are driven through this gear box and it provides two speeds forward and one speed reverse, as well as a neutral position. The neutral position is desirable as it permits of running the conveying and screening mechanism alone or in conjunction with the digging arms so as to clear the trench or the machine. The two speeds forward provide a varying speed ratio between the rate of advance of the machine and the rate at which the digging arms are operated. The reverse position is desirable as it provides maneuverability for the machine, and also permits of it being withdrawn from the head of the trench in case one of the digging arms strikes 120

125

130

a monument, or the like. The gear box 58 has a driven shaft 60 making a chain and sprocket connection 61 with a cross shaft 62. This cross shaft is in substantial alignment with the pivots 4 of the rear brackets 3. It carries sprockets 63 connected through chains 64 to sprockets 65 mounted on shafts 66 in the extensions 5 of the rear brackets 3. The shafts 66 carry the traction and supporting 10 wheels 7.

Frame supports and supporting rails

See particularly Figures 1, 3, and 8 to 11 inclusive.

15 The supporting wheels 6 and 7 run on rails 67 which are laid on the ends of the railroad ties by the workmen. The rails 67 are made in sections and are generally channel shaped. The channel web is punched with 20 spaced rectangular openings 68 which provide a rack for engagement by the teeth on the wheels 7. This insures positive advancing of the machine. Each rail 67 is provided with a flange plate 69 projecting upwardly from the supporting face of the rail. The flanges 69 guide the machine by engaging the sides of the rollers 6.

Each rail section is provided with side-wise extending pins 70 adapted to engage any 30 one of a series of notches 71 in an anti-creeper 72. The anti-creeper comprises a pair of connected side members 73 lying on either side of the rail and provided with hook portions 74 for engaging a side face of a rail-road tie. The hook portions 74 hold the rails in place and insure that the machine will be urged forward into the ballast to be dug.

Each rail 67 is provided adjacent each end with a pivoted arm 75. A locking bar 76 is 40 pivoted to the arm 75 and has its other end shaped to engage any one of the teeth of a ratchet bar 77 secured to the supporting rail. In operation the rail 67 is laid on the ties and the arms 75 are swung out to bear against 45 the track rail R. The arms are held in the adjusted position by the locking bars 76. Coil springs 75' hold the bars 76 in the desired notches. The ratchet bar 77, and the arms 75 and 76 carried thereby, are insulated from 50 the rail sections, as indicated at 77', so as to prevent interference with signal circuits.

Each rail section 67 is provided at one end with a pair of hook members 78, and at the opposite end with a corresponding pin 79. The 55 rails are thus positively connected together so as to provide a substantially continuous track. The hook members 78 lie inside the flanges of the channel forming the supporting rail and insure proper alignment of the sections. A joint between adjacent supporting rail sections is indicated in chain lines in Figures 8 and 9. When a rail is laid an anti-creeper 72 will be placed on a convenient tie and a pin 70 will engage one of the slots 71.

57 The adjustable arms 75 permit of shifting

the rail sections on the ties, as is necessary for tracks of varying center distances. The supporting wheels 6 provide smooth supporting members which permit of the machine rounding a curve. There is sufficient clearance for the sprocket teeth on the wheels 7 to permit of the machine rounding a curve without interfering with the positive driving action.

Where adjacent tracks lie at different levels, it is necessary to vary the relative height of the supporting arms 5 on the two sides of the machine. An adjustment of these arms is also desirable so as to permit of digging to different depths. The construction which permits of such an adjustment is best shown in Figures 2 and 11. Each bracket 3 is provided with teeth 80 in a portion of its periphery, and these teeth are engaged by a worm wheel 81 on a shaft 82, carried in a bearing bracket 83 secured to the frame 2. Each shaft 82 is provided with a squared head to accommodate a crank or wrench. Rotation of the shaft 82 serves to adjust the vertical height of the arm 5 on the bracket 3. The worm and sector is irreversible and therefore tends to hold the bracket in the adjusted position. As a matter of precaution, however, holding bolts 84 passing through slots 85 in the bracket are provided. The bracket carries indicia 86 for giving a direct reading of the amount of adjustment at any time.

With this arrangement of the supporting brackets it is possible to change the depth to which the machine digs, and also to maintain the machine horizontal even though the tracks are at different levels, and thus preserve the track clearance. The adjustment of the rear brackets does not interfere with the drive since the sprocket 65 is rotated about the center of the sprocket 63. With the machine maintained substantially horizontal there is no danger of it encroaching on the clear space required for rail traffic and defined by the chain lines shown in Figure 3.

Digging head and conveyor

See particularly Figures 1 to 7 inclusive.

As above stated, the digging head comprises the supporting plate 8 and the digging arms 9, each arm 9 being pivoted on the crank pin 42 carried by the disk 41. At its rear end each arm is pivoted to a connecting arm or link 87, each arm 87 being pivotally connected to the plate 8 at 88. In operation the crank disks 41 are rotated and the front ends of the arms 9 follow an orbital path. The motion is first outwardly and then forwardly. The arm then sweeps toward the center line of the machine and at the same time is retracted somewhat. It is then moved outwardly to repeat the stroke. As shown in Figure 6, the two arms are out of time with one another so that first one arm and then the

other sweeps the material toward the center of the machine where it will fall on the conveyor 11. Figure 3 shows how the arms dig under the ties and break down the impervious wall of material. During a part of the stroke, both arms lie over the plate 8, so that the machine can be readily inserted in the trench.

It will be noted that the arms 87 are bowed 10 away from the corresponding digging arm 9. A straight link tends to catch material between the two arms at a certain part of their stroke and cause breakage of the machine. The bowed connecting arm eliminates 15 this tendency to a large degree. It is further eliminated by the provision of beveled faces 89 on the arms 9 and 87, so that each arm presents a relatively narrow face to the other arm. The widest portions 20 of the arms 9 and 87 are those portions which are closest to the plate 8, so that any material between the arms is urged away from the plate by the inclined faces 89, and jamming is eliminated.

25 Each digging arm 9 is provided with a digging portion 90. The digging portion 90 projects between forks 91 on the arm 9 and is held by a pin 92 lying in a slot 93. The arm 90 is rockable toward or away from the 30 plate 8, but is normally urged thereagainst by a compression spring 94. The action of the spring is limited by a bolt 95. This arrangement permits of the digging portion 90 moving away from the plate in case the 35 material becomes jammed, thus preventing breakage. Each digging portion 90 is provided with two digging points 96 and 97. The point 96 is particularly effective for digging at the sides of the trench, providing 40 clearance for the outward sweep of the digging portion 90, while the point 97 is particularly effective for digging into the space directly ahead of the machine. The point 97 also aids materially in sweeping the material toward the conveyor 11.

45 The conveyor 11 comprises a pair of sprocket chains 98 extending from the head sprockets on the shaft 50 over idlers 99 to sprockets on a foot shaft 100. The sprocket 50 chains carry a conveying belt for the material. The top flight of the conveyor extends upwardly at an angle and then horizontally along the top of the machine. The bottom flight follows very closely the line of the top 55 flight. The gearing is such that the conveyor 11 is run at sufficient speed to carry away more material than the arms 9 can supply, so that the ballast normally does not tend to pile up and clog the digging operation. This arrangement is also desirable 60 since it prevents very large quantities of ballast from being dumped suddenly on the shaker screen. On the contrary, the ballast is supplied in a normally steady stream.

65 It will be noted from Figure 5 that the

worm 38 and worm wheel 39 and the bearings for the foot shaft 100 are all enclosed in boxes 101. These boxes are substantially dust proof and are filled with lubricant. Dirt guards 102 and 103 prevent grit from entering the boxes 101 either around the shaft 100 or under the crank disks 41.

Modified form of digging head

See Figures 14 and 15.

In the modified form of digging head parts corresponding to similar parts in the preferred embodiment of the invention have been given the same reference character with an "a" suffixed thereto. The arms 9 are replaced by arms 104 pivoted to the crank disks 41a at 105. Instead of the arms being connected to links, they are recessed as shown in Figure 15 so as to engage a roller 106 on a fixed stud 107. The arms 104 are curved so as to impart to the digging portions 90a the desired digging and sweeping movement. This arrangement is found in practice to be satisfactory, and the arrangement of the roller 106 and recess is such that wear, due to the action of grit, is minimized.

In either of the illustrated forms of digging head the digging portions 90 or 90a are readily replaceable in case they are bent, broken, or are unduly worn. Similarly, either the plate 8 or 8a is provided with a replaceable edge 108, which may be renewed as desired.

Shaker screen

See particularly Figures 1, 2 and 4.

The shaker screen 12 comprises a frame 109 carrying brackets 110 and 111 for connection to the shaker arms. The brackets 110 are connected through a shaft 112 to arms 113 pivoted on the frame at 114. The brackets 111 are connected through a shaft 115 to arms 116 pivoted on the shaft 62. It will be noted from Figure 2 that while the arms 113 are substantially vertical, the arms 116 are materially inclined. This arrangement imparts a very effective vibrating motion to the screen when the arms are rocked back and forth.

The shaft 115 carries one end of a connecting rod 117. The other end of the connecting rod is carried by an eccentric 118 on the shaft 52. As the shaft 52 rotates, it imparts a rapid rocking motion to the arms 116, thus vibrating the screen 12 and insuring proper screening.

The screened material falls into a hopper 119 from which it flows to the elevator 14 for removal.

Handling screenings

See particularly Figures 1, 2, 12 and 13.

The screenings elevator 14 comprises a casting 120, the foot shaft 54, a shaft 121, a sprocket chain 122 extending between the shafts 54 and 121, and a belt carried by the sprocket chain. Screenings in the hopper 119

70

105

110

115

120

125

130

flow to the elevator belt and are carried upwardly thereby to be discharged over the head shaft 121.

Figures 1 and 2 show a box 123 for receiving the screened material. These boxes are intended to be carried away by workmen as they are filled. In their filling position they are at substantially the tie level and there is no surrounding machinery to prevent their ready removal. When the machine is running at full speed, several boxes will be filled per minute, and the principal labor required for the machine is the handling of these boxes.

It will be noted from Figure 1 that the casing 120 of the elevator 14 lies under the discharge lip 13 of the shaker screen 12. Since the casing 120 is relatively narrow, and is positioned along the center line of the machine, its presence does not seriously interfere with the return of the ballast to the trench. In fact, the ballast is discharged to either side of the trench and therefore has a greater tendency to more uniformly back fill the trench. A guide member 124 is provided on the screen to direct the screened ballast away from the top of the elevator casing 120.

As above stated, the principal labor requirement for the machine is the handling of the dirt boxes 123. Figures 12 and 13 show a conveyor for discharging the dirt to the side of the right-of-way. Instead of the casing 120 having a bracket 125 for supporting and positioning the dirt boxes 123, Figures 12 and 13 show a conveyor frame 126 pivoted to the elevator frame 120a. The head shaft 121a is connected through mitre gears 127 to a vertical shaft 128, which in turn is connected through mitre gears 129 to a shaft 130 on the conveyor frame 126. A conveyor belt extends from the shaft 130 to a shaft 131 at the other end of the frame 126. A hopper 132 is mounted on the frame 126 adjacent the head of the screenings elevator, so as to catch the screenings and position them on the conveyor belt. The conveyor 126 is arranged to be swung around the shaft 128 so that the driving connection will not be interrupted. Figure 12 shows in solid lines the conveyor extending across a railroad track so as to discharge to the side of the right-of-way. In case a train comes along, the conveyor may be swung to the dotted line position of Figure 12, and then swung back again. The hopper 132 is arranged to swing on a stub shaft 133, so that it always maintains the proper relation to the screenings elevator. By swinging the conveyor 126 to different angular positions, the dirt may be discharged at varying distances from the tracks, as desired. The gear and shafts 127, 128 and 129 are duplicated on the two sides of the machine. By shifting the supporting bracket by which the conveyor is mounted on a shaft 128 to the other side of the machine, the conveyor

may be used to discharge to the other side of the right-of-way.

While I have illustrated and described the present preferred form of my invention, it will be understood that it may be otherwise embodied within the scope of the following claims.

I claim:

1. A railway ballast treating machine comprising a frame adapted to lie between the ends of the ties of adjacent railroad tracks and to travel along the track-way, supporting rails adapted to lie on the ties, and means adjustably connected to said rails for engaging said ties.

2. A railway ballast treating machine comprising a frame adapted to lie between the ends of the ties of adjacent railroad tracks and to travel along the track-way, supporting rails adapted to lie on the ties, and an anti-creeper for a supporting rail arranged to engage a tie.

3. A railway ballast treating machine comprising a frame adapted to lie between the ends of the ties of adjacent railroad tracks and to travel along the track-way, supporting rails adapted to lie on the ties, and an anti-creeper for a supporting rail arranged to engage a tie, the anti-creeper being adjustable to different positions along the supporting rail.

4. A railway ballast treating machine comprising a frame adapted to lie between the ends of the ties of adjacent railroad tracks and to travel along the track-way, supporting rails adapted to lie on the ties, and an anti-creeper for a supporting rail arranged to engage a tie, the track being so formed as to provide a positive driving connection for the frame.

5. A railway ballast treating machine comprising a frame adapted to lie alongside a railroad track, a supporting rail for the frame adapted to lie on the ties, and adjustable means engaging the track rail for spacing the supporting rail therefrom.

6. A railway ballast treating machine comprising a frame adapted to lie alongside a railroad track, a supporting rail for the frame adapted to lie on the ties, means for engaging the track rail spacing the supporting rail therefrom, and means insulating the supporting rail from the track rail.

7. A railway ballast treating machine comprising a frame adapted to lie alongside a railroad track, a supporting rail for the frame adapted to lie on the ties, an arm secured to the supporting rail and adapted to bear against the track rail, and means holding the arm in varying angular positions.

8. A digging machine comprising a frame, a crank mounted thereon, a link pivotally mounted on the frame, and a digging arm secured to the link and to the crank, the link being curved so as to provide a rela-

tively wide space between the link and the arm.

9. A digging machine comprising a frame, a crank mounted thereon, a digging arm secured to the crank, and a connecting arm pivoted to the digging arm and to the frame, one of the arms having a face inclined so as to present a relatively narrow edge to the other arm.

10. 10. A digging machine comprising a supporting plate, a rotatable disk substantially flush therewith, a digging arm connected to the disk, and a connecting arm pivoted to the digging arm and to the plate, one of the arms having a face inclined so as to present a relatively narrow edge to the other arm, said relatively narrow edge being located adjacent the plate.

In testimony whereof I have hereunto set
20 my hand.

JAMES B. McWILLIAMS.
